UNITED STATES PATENT OFFICE.

ALBERT D. CROSSLEY, OF SOUTH NORWALK, CONNECTICUT.

TROLLEY-WIRE HANGER.

SPECIFICATION forming part of Letters Patent No. 679,953, dated August 6, 1901.

Application filed December 20, 1900. Serial No. 40,557. (No model.)

To all whom it may concern:

Be it known that I, ALBERT D. CROSSLEY, a citizen of the United States, residing at South Norwalk, county of Fairfield, State of Connecticut, have invented a new and useful 5 Trolley-Wire Hanger, of which the following is a specification.

My invention has for its object to provide a trolley-wire hanger that will do away with 10 all soldering of the wire, will bend the wire but slightly, and will provide a smooth surface practically continuous with the wire for the trolley to travel upon, the bearing-surface of the hanger being relatively long and amply 15 thick to stand the requirements of use for practically an unlimited length of time and the hanger proper consisting of but two members, both of which shall be relatively light and both of which may be cast to the required 20 shape and will need practically no finishing whatever, thereby insuring the maximum of efficiency and durability at a minimum cost.

With these ends in view I have devised the simple and novel trolley-wire hanger of which 25 the following description, in connection with the accompanying drawings, is a specification, reference characters being used to designate the several parts.

Figure 1 is an elevation of my novel trolley-wire hanger, the lower member being 30 partly broken away; Fig. 2, a plan view, the threaded shank of the insulator being in section on the line 2 2 in Fig. 1; Fig. 3, an elevation of the upper member detached, and 35 Fig. 4 is a transverse section on the line 4 4 in Fig. 1.

A denotes the insulator, which is shown as 40 provided with a threaded shank 10. It should be understood that the insulator forms no portion of my present invention, my novel hanger being adapted for use in connection with any of the ordinary insulators now upon the market.

B denotes one member of my novel hanger, 45 which for convenience I will term the "lower" member, and C the other member, which for convenience I will term the "upper" member. Member B comprises an elongated trough 11, which is adapted to receive the 50 trolley-wire D, the bottom of the trough being made thickest at its mid-length, as at 12,

so as to provide an amount of metal for wearing purposes amply sufficient to withstand long-continued usage. From the thick portion 12 at the center of the trough the metal 55 diminishes in thickness with a slow taper toward both ends, so that the thick portion of the bottom is but slightly higher than any other portion, thus requiring but a slight bend of the trolley-wire, and the under side of the 60 hanger is but slightly lowest at the center, so that the trolley will pass on and off the hanger easily and without appreciable shock at either end thereof. At the top of member B is a slotted hub 13, which is internally 65 threaded to receive the threaded shank 10 of the insulator, the split or slot through the hub, which I have indicated by 14, being continuous with the trough, so as to permit the trolley-wire to pass into the trough. 70

Member C comprises a clamping-piece 15, which is adapted to just pass through slot 14 and into the trough, and a ring 16, which just passes over the hub, as clearly shown in the drawings. The lower side of the clamping- 75 piece is curved longitudinally (see Fig. 3) to correspond with the curvature of the bottom of the trough and is provided with a longitudinal groove 17, whose transverse curvature is the reverse of the transverse curvature of 80 the bottom of the trough, so that a trolley-wire will be gripped firmly between the two curved surfaces. The top of the ring is made slightly higher than the top of the hub, as clearly shown in Fig. 3, so that when the 85 threaded shank of the insulator is turned down to place in the hub the insulator will engage the top of the ring, as clearly shown in Fig. 4, and when the insulator is tightened in the clamping-piece, which is made integral 90 with the ring, will be forced down upon a trolley-wire lying in the trough, thereby locking the wire tightly to the hanger. In order to strengthen the connection of the ring to the clamping-piece, lugs 18 may be cast upon 95 the inner side of the ring, which in the assembled position will engage the slot in the hub. This, however, is a mere detail of construction that does not go to the merits of the invention. In order to insure that member B cannot possibly become separated from member C, even should the latter by any pos- 100

sibility become separated from the insulator, I have shown lugs 19 on the under side of the ring, which after the parts are assembled in use are adapted to be turned into recesses 5 20 on the outer side of the hub.

The operation of connecting a trolley-wire to the hanger is so simple as to hardly require further explanation and will, it is believed, be readily understood from the drawings. The operator places the trolley-wire in the trough in member B, then places the clamping-piece of member C in the trough over the wire, the ring on member C passing over the hub on member B. The threaded shank of the insulator is then turned down to place in the hub, the under side of the insulator engaging the top of the ring and forcing the clamping-piece down upon the trolley-wire, which is thus securely gripped 15 between the clamping-piece and the bottom of the trough.

Having thus described my invention, I claim—

1. A trolley-wire hanger consisting of members B and C, said member B comprising an elongated trough of rigid unyielding material having a bottom made thickest at its mid-length and integral with the sides and diminishing in thickness toward both ends and a 25 hub having a slot continuous with the trough, said slot having a permanent width sufficient to receive the trolley-wire, and said member C comprising a clamping-piece adapted to pass within the trough and a ring adapted to 30 pass outside the hub, the lower side of said clamping-piece being curved longitudinally to correspond with the curvature of the bottom of the trough and having a longitudinal groove to receive a trolley-wire which is securely locked between the trough and the 35 clamping-piece.

2. A trolley-wire hanger consisting of members B and C, said member B comprising an elongated trough of rigid unyielding material 45 having a bottom made thickest at its mid-length and integral with the sides and diminishing in thickness toward both ends and a hub having a slot continuous with the trough, said slot having a permanent width sufficient 50 to receive the trolley-wire, and said member C comprising a clamping-piece adapted to pass within the trough and a ring adapted to pass outside the hub, the lower side of said clamping-piece being curved longitudinally 55 to correspond with the curvature of the bottom of the trough and having a longitudinal groove to receive a trolley-wire and said ring standing higher than the hub so that when either of said members is held and the other 60 member moved toward it the trolley-wire will be clamped between said members.

3. A trolley-wire hanger consisting of members B and C, said member B comprising an elongated trough of rigid unyielding material

having a bottom made thickest at its mid-length and integral with the sides and diminishing in thickness toward both ends and a hub having a slot continuous with the trough, said slot having a permanent width sufficient 65 to receive the trolley-wire, and an internal screw-thread adapted to engage the shank of an insulator, and said member C comprising a clamping-piece adapted to pass within the trough and a ring adapted to pass outside the hub and to be engaged by an insulator when 70 the shank of the latter is turned down to place in the hub so that a trolley-wire will be locked between the clamping-piece and the 75 bottom of the trough.

4. A trolley-wire hanger consisting of members B and C, said member B comprising an elongated trough having a bottom made thickest at its mid-length and diminishing in thickness toward both ends and a hub having a slot continuous with the trough and recesses 80 20, and member C comprising a clamping-piece adapted to pass within the trough and a ring adapted to pass outside the hub and having lugs adapted to be turned into the recesses, whereby the members may be locked 85 together in use independently of the insulator.

5. The combination with member B having a trough of rigid unyielding material with integral sides and bottom to receive a trolley-wire and a hub having a slot continuous 95 with the trough and an internal screw-thread adapted to engage an insulator-shank, said slot having a permanent width sufficient to receive the trolley-wire, of a member C having a clamping-piece adapted to pass within the trough and a ring which passes outside the hub and stands higher than the hub so that when the shank of an insulator is turned down in the hub the insulator will engage the 100 ring but not the hub, substantially as described.

6. A trolley-wire hanger consisting of members B and C, said member B comprising an elongated trough of rigid unyielding material 110 having a bottom made thickest at its mid-length and integral with the sides and diminishing in thickness toward both ends and a hub having a slot continuous with the trough, said slot having a permanent width sufficient 115 to receive the trolley-wire, and said member C comprising a clamping-piece adapted to pass within the trough and a ring adapted to pass outside the hub and to be engaged by an insulator when assembled, substantially 120 as described.

In testimony whereof I affix my signature in presence of two witnesses.

ALBERT D. CROSSLEY.
